[57] **CLAIM**

The ornamental design for a flower pot cover, as shown and described.

DESCRIPTION

FIG. 1 is a perspective view of my new flower pot cover design;

FIG. 2 is a side elevational view thereof;

FIG. 3 is a top plan view thereof;

FIG. 4 is a bottom plan view thereof;

FIG. 5 is a side elevational view of a second embodiment of the design of FIG. 1, the only difference being the height; and,

FIG. 6 is a side elevational view of a third embodiment of the design of FIG. 1, the only difference being the height.

The flower pot cover has no substantial thickness.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 361,738
DATED : August 29, 1995
INVENTOR(S) : Jon S. Shryock
